UNITED STATES PATENT OFFICE.

FREDERICK MITCHELL, OF BROOKLYN, NEW YORK.

INKSTAND.

SPECIFICATION forming part of Letters Patent No. 378,208, dated February 21, 1888.

Application filed December 22, 1887. Serial No. 258,674. (No model.)

To all whom it may concern:

Be it known that I, FREDERICK MITCHELL, of Brooklyn, in the county of Kings and State of New York, have invented a new and Improved Inkstand, of which the following is a full, clear, and exact description.

This invention relates to inkstands containing more than one ink-holder, and has for its object to provide a double inkstand in which one inkstand serves as a cover for another beneath, and in which the parts are detachable, so that the inkstand may be convertible into a single inkstand, or be used as a double inkstand, as desired.

15 The invention consists in an inkstand constructed and arranged as hereinafter described and claimed.

Reference is to be had to the accompanying drawings, forming a part of this specification, 20 in which similar figures of reference indicate corresponding parts in all the views.

Figure 1 is a perspective view of the invention. Fig. 2 is a vertical section thereof; and Fig. 3 is a sectional view showing the invention converted into a single inkstand. Fig. 4 25 is a sectional view of a modification.

In the construction of this invention an inkstand, 1, is mounted on a suitable base, 2, and may be integral therewith, as shown, or detached and resting in a socket therein, or connected thereto in any way desired. To the inkstand 1 is pivoted an inkstand, 3, by any suitable means, and, as shown, by a pin, 4, located in holes or sockets 5 in the top of inkstand 1 and bottom of inkstand 3, so that inkstand 3 resting on inkstand 1 serves as a cover to the latter, and may be swung to one side, as shown in Fig. 1, when the inkstand 1 is required for use.

40 The inkstand 3 is provided with a cover, 6, pivoted by means of a pin, 7, secured to the cover 6, and projecting into a socket, 8, in the top of the inkstand 3. By means of the foregoing construction, when it is desired to use 45 the inkstand 1 as a single inkstand, the cover 6, with its pivot-pin 7, may be removed from the inkstand 3 and the latter lifted off from the inkstand 1. The pin 4, which has remained in the socket 5 of inkstand 1, is then taken 50 out, and the cover 6 applied to the inkstand 1 by inserting its pin 7 in the socket 5, in this way providing a single inkstand, as shown in Fig. 3.

In lieu of the construction heretofore described, 55 the inkstand 14, resting on inkstand

1, may be provided with a hole or perforation, 9, extending through the inkstand at one corner, as shown, and a pin, 10, may be inserted through hole 11 in a cover, 13, and through hole 9 in inkstand 14, and have its end projecting into socket 5 of inkstand 1. In this construction to convert the inkstand 1 into a single inkstand, a separate pin, 4, as shown in Fig. 2, would have to be employed in connection with the cover 13 and sockets 5 and 11. 65 It is obvious that any form of pivot-joints may be used to convert the double inkstand into a single inkstand.

By means of this invention economy of space is attained, as by having one inkstand resting 70 on another a smaller base may be employed. It is also obvious that ink-cups may be used with the inkstands and rest therein, and that the inkstand may be of any shape desired. The inkstand herein described may contain two 75 different kinds of ink, and access can readily be had thereto by simply moving the upper inkstand aside or the cover of the upper inkstand.

The inkstand may be made of glass or wood, 80 or other suitable material, or partly of glass or partly of metal or wood, as desired.

Having thus described my invention, I claim as new and desire to secure by Letters Patent—

1. A double inkstand consisting of one inkstand pivoted to and resting upon another, 85 forming a cover thereto, and provided with a suitable cover, substantially as described.

2. The combination, with an inkstand, of an inkstand connected thereto by a detachable 90 pivot-pin, and resting thereon to form a cover, and having a detachable cover pivoted thereto, substantially as described.

3. A double inkstand consisting of an inkstand with a detachable cover resting upon another inkstand and serving as a cover thereto, and connected therewith by a detachable pivot-connection, substantially as described.

4. A double inkstand consisting of inkstand 1, having the base 2, and the inkstand 3, having the cover 6 pivoted thereto by means of pin 7, resting in the socket 8, the inkstand 3 being pivoted to the inkstand 1 by means of pivot-pin 4, resting in the sockets 5 of the inkstand 3 and inkstand 1, substantially as described. 100 105

FREDERICK MITCHELL.
